United States Patent Office

Des. 230,545
Patented Mar. 5, 1974

230,545

WINE CABINET

Florent L. Mouchon, 23 Hebert St.,
West Warwick, R.I. 02886

Filed July 31, 1972, Ser. No. 276,359

Term of patent 14 years

Int. Cl. D6—04

U.S. Cl. D6—189

FIG. 1

FIG. 3

FIG. 4

FIG. 2

FIG. 5

FIG. 6

FIG. 1 is a front perspective view of a wine cabinet showing my new design;

FIG. 2 is a front elevational view thereof;

FIG. 3 is a rear elevational view thereof;

FIG. 4 is a side elevational view thereof;

FIG. 5 is a top plan view thereof; and

FIG. 6 is a bottom plan view thereof.

I claim:

The ornamental design for a wine cabinet, substantially as shown.
